(57) **CLAIM**

The ornamental design for a mobile phone, as shown and described.

DESCRIPTION

FIG. 1 is a front view of a mobile phone showing our new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The broken line showing of the mobile phone is for the purpose of illustrating unclaimed portions of the mobile phone and forms no part of the claimed design.

1 Claim, 6 Drawing Sheets(56)
